SWITCHING DEVICE

Walter Hoppe, Yverdon, Switzerland, assignor to El-Re-Ma S. A., Lugano, Switzerland

Application May 21, 1953, Serial No. 356,577

Claims priority, application Switzerland December 6, 1952

5 Claims. (Cl. 200—87)

The present invention relates to a switching device, and more particularly to a switching device for use in electro-technical apparatus, more particularly in calculating machines having relays, and comprises two groups of contact pieces one of which is fixed and the other is movable, one of the groups of contact pieces being arranged for displacement with regard to the contact pieces of the other group.

In order to assure a good electrical contact the movable contact pieces have to exert a sufficient pressure on the fixed contact pieces with which they have to establish the electric contact. This leads to relatively large frictional forces when the movable contact pieces are displaced with respect to the fixed contact pieces so that the force required for producing the displacement is great and the wear and tear of the contact pieces is considerable. The strong force required in the known switching devices for producing the displacement presents a serious drawback when the energy which can be used for producing the displacement is limited.

It is an object of the present invention to avoid these drawbacks.

Other objects and advantages will be apparent from a consideration of the specification and claims.

A contacting device according to the present invention comprises in combination a group of fixed contact pieces, a group of movable contact pieces, the contact pieces of one of the groups being displaceable with respect to the contact pieces of the other group so that at least one of the movable contact pieces is opposite to at least one predetermined contact piece of the fixed contact group, the contact pieces of at least one of the groups consisting at least partly of magnetic material, and an electric coil arranged so as to surround the contact pieces consisting of magnetic material, the electric coil causing by the energization thereof an attraction of at least one of the movable contact pieces toward the fixed contact piece being opposite thereto so as to establish a firm electrical contact therebetween.

The accompanying drawing shows schematically and by way of example two embodiments of the present invention.

In the drawings

Fig. 1 is a side view of a first embodiment of the invention;

Fig. 2 is a section taken along the line II—II of Fig. 1;

Fig. 3 is a plan view of a second embodiment of the invention; and

Fig. 4 is a section taken along the line IV—IV of Fig. 3.

Referring now to the drawings and first to Figs. 1 and 2, the contacting device comprises a group of nine fixed contact pieces 1 which are carried by an insulating body 3 as more fully described hereinafter, and a group of three movable contact pieces 2 which are arranged in recesses of an insulating body 4. The latter is connected with two rods 5 by two resilient rings 6, respectively, the rods 5 sliding in bores provided in the body 3. The body 4 and contact pieces 2 supported by the same are thus capable of displacement with respect to the contact pieces 1 and the body 3 by means of a longitudinal movement of the rods 5.

Each movable contact piece 2 is provided with a central rod-like portion 7 which traverses the body 4 and is

2

provided with a groove 10 near the extremity thereof. The ends of the portions 7 are soldered to respective connecting wires (not shown). The upper parts of the portions 7 traverse helicoidal springs 8, respectively, which abut against the body 4, and a resilient annulus 9 arranged in each of the grooves 10 of the portions 7. The springs 8 have the task of urging the movable contact pieces 2 associated therewith into positions in which they are kept at a distance from the fixed contact pieces 1.

Referring now to Fig. 2 it is seen that the fixed contact pieces 1 consist of U-shaped lamellae which are partly embedded in the insulating body 3. These lamellae consist of magnetic material and have mid portions surrounded by an electric coil 12. Each lamella forms thus a part of a magnetic circuit for the coil 12 and serves at the same time as an electrical contact piece. To this effect each lamella 1 is provided with an extension 11 which allows to connect to it a connecting wire (not shown) by soldering. Each movable contact piece 2 has the general form of a plate and consists also of magnetic material so that the assembly of a fixed contact piece and a movable contact piece forms an elementary magnetic circuit comprising two air gaps.

The operation of this device is as follows:

As long as the coil 12 is not connected to a voltage source the movable contact pieces 2 are held apart from the fixed contact pieces 1 by the action of the springs 8. In consequence thereof it is possible to displace the body 4 and thus the movable contact pieces with regard to the fixed contact pieces 1 without having to overcome the friction between the contact pieces of one group and those of the other group; therefore, the energy necessary for producing these displacements is as low as possible. When the movable contact pieces 2 have been brought in opposition to the desired fixed contact pieces 1 the coil 12 is put under voltage so that a magnetic field results which provokes the attraction of the movable contact pieces 2 which are displaced parallel to the principal plane thereof and in direction of the fixed contact pieces 1. The electrical contact established between the fixed and movable contact pieces is stable and lasts as long as the coil 12 is excited.

The surfaces which make contact with one another are preferably covered by a layer of non-magnetic material such as silver having good electrical conductive properties in order to assure a good contact and to diminish the remanence of the magnetic circuit. This layer can be applied for instance by electrolysis, by hot spray metallization, or by soldering. The contact surfaces of certain contact pieces, for instance the movable contact pieces, can be slightly rounded as indicated at 13 in order to produce a concentration of the magnetic flux and thus to obtain an elevated contact pressure.

In another embodiment of the invention the contact pieces 2 are fixedly embedded in the insulating body 4 and movable contact pieces 1 are disposed within the insulating body 3. As soon as the coil 12 is excited the contact pieces 1 are displaced toward the contact pieces 2. The contact pieces 1 can be maintained at a distance from the movable contact pieces by means of one or several resilient elements or simply by their own weight.

In a contact device such as shown in Figs. 1 and 2, I may also omit the springs 8 returning the contact pieces 2 to the original position thereof. Thus the latter would continually rest on the contact pieces 1; however, as the weight thereof is very slight the supplemental friction resulting therefrom would be exceedingly weak. Such an arrangement could obviously only be adopted in a plant the operation of which is not impeded by the contact which are produced between the fixed contact pieces and the movable contact pieces during the lateral displacement of the latter. The arrangement according to Figs. 1 and

2 could also be mounted so that the contact pieces 2 are below the contact pieces 1. In this way, it is possible to omit the springs 8, the contact pieces 2 being held by their own weight in a position away from the contact pieces 1.

In the embodiment shown in Figs. 3 and 4 the movable contact pieces have the form of thin plates 14 consisting of magnetic material and arranged on a sector 15 of insulating material in prolongation of the radii thereof. The sector 15 is pivotable about the shaft 16. The fixed contact pieces are formed each by two substantially U-shaped parts 17. Each of the parts 17 is attached to one extremity of a leaf spring 18. The two leaf springs 18 are attached to a block 19 consisting of insulating material and are electrically connected to each other by means of a rivet 21. The current can be led into the portions 17 advantageously by means of connecting wires (not shown) attached to one of the leaf springs 18. A connecting wire (not shown) is electrically connected to each of the movable contacts. The two portions 17 are so held by the leaf springs 18 that the outer ends of their branches are disposed opposite to each other and form between themselves two air gaps. The plates 14 are capable of being arranged in one of the air gaps, whereas the branches of the portions 17 which form the other air gaps are surrounded by a coil 20. When the coil 20 is fed with a current the two portions 17 are attracted toward each other by the magnetic field which is produced, and the plate 14 is held between the two portions 17. From this results an excellent electrical contact between the portions 17 and the plate 14. When the coil 20 is not excited, the two portions 17 move away from each other and it is possible to displace the movable contact pieces 14 between the two portions 17 of the fixed contact pieces by rotating the shaft 16.

Also in this embodiment the surfaces which come into contact with one another are covered by a material having a good electrical conductivity such as silver. In a further modification the plates 14 consist of non-magnetic material having a good conductivity, for instance copper.

The embodiments which have been described hereinabove have as their main advantage that the displacement of the movable contact pieces is effected without any other effort besides that exerted by the forces of friction of their support and the forces of inertia. The forces of friction of the movable contact pieces against the fixed contact pieces which usually play the greatest part in the known contacting devices are here practically eliminated. At the same time the wear of the contact faces due to the friction at the displacement thereof is also eliminated. The safety of the contact is very large because in each case a double contact is formed and the contact pressure is high. The latter is in fact due to the attracting force of the magnets which is diminished only by the force of retraction of the springs which, however, is relatively weak.

It is to be understood that the number of the contact pieces of each group may be different from those indicated in the embodiments described hereinabove; particularly, contact devices can be provided which comprise only one movable contact piece which cooperates with a plurality of fixed contact pieces.

While I have illustrated and described the invention as embodied in a switching device for calculating machines, I do not intend to be limited to the details shown, since various modifications and structural changes may be made without departing in any way from the spirit of my invention.

What I claim is:

1. An electrical switching device comprising in combination, a stationary insulating body having a plurality of recesses; a group of fixed contact pieces arranged, respectively, in said recesses, each of said fixed contact pieces being constituted by a U-shaped lamella of mag-

netic material; electric coil means surrounding at least partly said fixed contact pieces; and at least one movable contact piece consisting at least partly of magnetic material, said movable contact piece being displaceable into at least two positions opposite to and spaced from said fixed contact pieces so as to selectively make contact therewith on energization of said coil means.

2. An electrical switching device comprising two insulating bodies having opposite conforming faces, one of said bodies being stationary and provided with supports for the other body, said other body being longitudinally displaceable with respect to said stationary body, magnetic material containing contact pieces in equally and uniformly spaced relationship in said opposite faces of said insulating bodies, bores in the displaceable insulating body, the contact pieces of said displaceable insulating body consisting of plates provided with rod-like extensions engaging said bores, the contact pieces in the stationary insulating body consisting of a plurality of superposed U-shaped lamellae, and electric coil means at least partly surrounding said superposed lamellae.

3. An electrical switching device comprising two insulating bodies having opposite conforming faces in closely spaced relationship, one of said bodies being stationary and provided with supports for the other body, said other body being longitudinally displaceable with respect to said stationary body, magnetic material containing contact pieces in equally and uniformly spaced relationship in said opposite faces of said insulating bodies, bores in the displaceable insulating body, the contact pieces of said displaceable insulating body consisting of plates provided with rod-like extensions slidably engaging said bores, the contact pieces in the stationary insulating body consisting of a plurality of superposed U-shaped lamellae, electric coil means at least partly surrounding said superposed lamella, and spring means normally holding the contact pieces of the displaceable insulating body at a distance from the contact pieces of the stationary insulating body, contact being established on energization of said coil means.

4. An electrical contact device comprising a stationary insulating body, a group of fixed contact pieces in said body, a movable insulating body slidably arranged for displacement in a plane parallel to said stationary body in closely spaced relationship thereto, a group of magnetic contact pieces in said movable body, said latter contact pieces being movable at right angles to said plane and selectively placeable in opposition to the contact pieces of said stationary body by displacement of said movable body, and electric coil means in said stationary body surrounding said group of fixed contact pieces, said electric coil means causing on energization thereof attraction between said opposite fixed and movable contact pieces and establishing a firm electric contact therebetween.

5. An electrical contact device as defined in claim 4 wherein said group of fixed contact pieces contains a greater number of contact pieces than said group of movable contact pieces.
